CONTAINER FOR PAINT, APPLICATOR AND RUBBING COMPOUND

John W. Madeira, Akron, Ohio, assignor to Plasti-Kote
Company, a division of Consolidated Foods, Inc.,
Medina, Ohio

Filed Dec. 10, 1970, Ser. No. 26,396

Term of patent 14 years

Int. Cl. D9—03

U.S. Cl. D9—196

FIG. 1

FIG. 3

FIG. 1 is a perspective view of a container for paint, applicator and rubbing compound showing my new design;

FIG. 2 is a top plan view thereof;

FIG. 3 is a bottom plan view thereof.

I claim:

The ornamental design for a container for paint, applicator and rubbing compound, as shown.
